Primary Examiner—Kay H. Chin[57] CLAIM

The ornamental design for a motorized wheelchair, as shown and described.

DESCRIPTION

FIG. 1 is a right side elevational view of a motorized wheelchair showing my new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a front perspective view thereof;

FIG. 8 is a right side elevational view of a second embodiment of the motorized wheelchair, the sole difference from the first embodiment being in the lack of optional lights;

FIG. 9 is a front elevational view of FIG. 8;

FIG. 10 is a rear elevational view of FIG. 8;

FIG. 11 is a left side elevational view of FIG. 8;

FIG. 12 is a top plan view of FIG. 8; and,

FIG. 13 is a front perspective view of FIG. 8.
